UNITED STATES PATENT OFFICE.

WILLIAM M. WHITE, OF MILWAUKEE, WISCONSIN.

HYDRAULIC ROTOR.

Application filed June 5, 1926. Serial No. 113,907.

This invention relates in general to improvements in the art of hydraulics, and relates more specifically to improvements in the construction and operation of rotors for hydraulic machines or the like.

An object of the invention is to provide a new and useful rotor which is simple in construction and efficient in operation. Another object of the invention is to provide an improved rotor structure especially applicable to hydraulic turbines having high specific speed. A further object of the invention is to provide an improved method of manufacturing compound turbine or pump rotors. These and other objects and advantages will be apparent from the following description.

In the construction of high speed turbines of the axial flow type, the rotor usually comprises a series of radiating vanes associated with a relatively large central hub. The use of such a large hub is desirable in order to dispose the vanes at some distance from the rotor axis whereby high peripheral speed is obtainable. These large hubs are however objectionable since the space occupied thereby is practically useless. The present invention contemplates provision of means whereby the hub space may be utilized for power converting purposes, and with this object in view, comprises the provision of active vanes in the space ordinarily utilized by the hub in turbines having high specific speed characteristics.

A clear conception of an embodiment of the invention and of the manner of manufacturing rotors in accordance therewith, may be had by referring to the drawing accompanying and forming a part of this specification in which like reference characters designate the same or similar parts in the various views.

Fig. 1 is a top view of an improved compound rotor for a hydraulic turbine.

Fig. 2 is a central vertical section through one of the improved rotors and through a fragment of the fluid supply casing associated therewith.

The improved rotor specifically illustrated in the drawing, comprises in general, a hub 4 rigidly attached to an end of the main shaft 5 and having an annular inner series of overlapping vanes 2 rigidly attached thereto. The ends of the vanes 2 remote

5 from the hub 4 are formed integral with a shroud ring 11, this ring having an outer tapered surface enlarging in diameter in the direction of flow of fluid past the ring. A second ring 9 having a tapered surface coacting with the tapered surface of the shroud ring 11 is detachably connected to the shroud ring 11 by means of fastenings 10 which may assume the form of rivets, bolts, screws, or otherwise. An annular outer series of non-overlapping vanes 3 are formed integral with the second ring 9 and extend radially with respect to the central axis of the rotor. The vanes 3 have free outer ends cooperating with an internal surface of the lower casing 7, and the hub 4 has an outwardly extending flange cooperating with an upper casing 6. The casings 6, 7 provide an inlet passage 8 for conducting water inwardly through the spaces between the inner vanes 2, and axially of the rotor through the spaces between the outer vanes 3, to a common draft tube associated with the discharge side of the rotor.

In constructing the compound rotor, comprising the hub 4, vanes 2, shroud ring 11, second ring 9, and vanes 3, the second ring 9 and vanes 3 are preferably cast separate from the remaining structure. The tapered surface of coaction between the rings 9, 11 may be readily machined and these elements 85 may thereafter be conveniently assembled and united with fastenings 10. By tapering the surfaces of coaction in the manner shown, the second ring 9 will be driven along the taper of the shroud ring 11 by the action of the water passing through the rotor.

It will be apparent that with this invention the high speed rotor vanes 3 may readily be disposed at any desired distance from the rotor axis without necessarily wasting the space which would otherwise be occupied by the rotor hub.

The inner vanes 2 are designed with low speed characteristics and may therefore be brought relatively close to the turbine axis. The inner series also comprises a greater number of vanes 2 than the outer series, and the vanes 3 of the outer series are spaced apart circumferentially. Both series of vanes are capable of being so designed that the characteristics thereof will cause the two sets of vanes to cooperate to produce a single highly efficient compound turbine 105 rotor.

It should be understood that it is not desired to limit the invention to the exact de-

tails of construction herein shown and described, for various modifications within the scope of the claims may occur to persons skilled in the art.

5. It is claimed and desired to secure by Letters Patent:

1. In combination, a rotor structure comprising a central portion having an outer tapered surface and a series of outwardly extending vanes attached to a ring having an inner tapered surface coacting with said outer surface.

10 2. In a rotor, a hub, a series of vanes attached directly to said hub, a shroud ring rigidly associated with said vanes remote from said hub, a second ring detachably secured to said shroud ring, and a second series 15 of vanes rigidly attached to said second ring.

20 3. In a rotor, a hub, a series of vanes attached directly to said hub, a shroud ring associated with said vanes and having a tapered surface, a second ring having a surface engaging said tapered shroud ring surface, and a second series 25 of vanes rigidly attached to said second ring.

25 4. In a rotor, a hub, a series of vanes attached directly to said hub, a shroud ring associated with said vanes and having a tapered surface enlarging in diameter in the direction of flow of fluid therealong, a second ring having a tapered surface coacting with said shroud ring surface, and a second series 30 of vanes rigidly attached to said second ring.

35

5. In a rotor, a hub, a series of vanes attached directly to said hub, a shroud ring rigidly attached to the ends of said vanes remote from said hub, a second ring detachably secured to said shroud ring, and a second series 40 of vanes rigidly attached to said second ring, the vanes of said second series having free outer ends.

6. In a rotor, a hub, a series of overlapping vanes attached directly to said hub, a shroud ring formed integral with the ends of said vanes remote from said hub, said shroud ring having a tapered surface enlarging in diameter in the direction of flow of fluid therealong, a second ring detachably connected to said shroud ring at said tapered surface, and a second series of non-overlapping vanes formed integral with said second ring, the vanes of said second series 45 having free outer ends.

50 7. In a rotor, a hub, a series of vanes attached to said hub and extending longitudinally of the axis of said rotor, a shroud ring rigidly associated with the ends of said vanes remote from said hub, a second ring 55 detachably connected to said shroud ring, and a second series of vanes rigidly associated with said second ring and radiating from said axis, the vanes of said second series being fewer in number than those of said first mentioned series.

In testimony whereof, the signature of the inventor is affixed hereto.

WILLIAM M. WHITE.
